UNITED STATES PATENT OFFICE.

JOHN P. LASATER, OF PARIS, TENNESSEE.

DESIGN FOR A BOTTLE.

Application filed May 19, 1927. Serial No. 22,098. Term of patent 7 years.

To all whom it may concern:

Be it known that I, JOHN P. LASATER, a citizen of the United States, residing at 404 North Poplar St., city of Paris, in the county of Henry and State of Tennessee, have invented a new, original, and ornamental Design for Bottles, of which the following is a specification, reference being had to the accompanying drawing, forming part thereof.

The figure is a side view in elevation of a bottle, showing my new design.

I claim:

The ornamental design for a bottle, as shown.

JOHN P. LASATER.
